(57) **CLAIM**

The ornamental design for a safety railing having a buoy holder, as shown and described.

DESCRIPTION

FIG. 1 is a front perspective view of a safety railing having a buoy holder according to our new and ornamental design; FIG. 2 is a rear perspective view thereof; FIG. 3 is rear elevation view thereof; FIG. 4 is a front elevation view thereof; FIG. 5 is a side view thereof; FIG. 6 is an opposite side view thereof; FIG. 7 is a top view thereof; and, FIG. 8 is a bottom view thereof. The broken lines in the drawings illustrate portions of the safety railing having a buoy holder and buoys that form no part of the claimed design.
